AIR COOLER SYSTEM HAVING TEMPERA-
TURE AND HUMIDITY CONTROLLING
MEANSWarren A. Spofford, Glen Ridge, N. J., assignor
to General Electric Company, a corporation of
New York

Application October 25, 1947, Serial No. 782,060

6 Claims. (Cl. 62—6)

1

This invention relates to air cooling systems employing refrigerating machines of the compression type and particularly to arrangements for controlling the operation of the refrigerant evaporators of such systems.

In the operation of air cooling systems it is desirable to control both the temperature and humidity of the air in the space to be cooled. Various arrangements have been proposed for controlling both temperature and humidity and it has been found desirable to provide a "modulating" control, in other words, a control which operates continuously to vary the temperature or humidity gradually or by small increments without interruption of the operation of the cooling unit. This modulating action may be secured, for example, by variable throttling of the flow of liquid refrigerant supplied to the evaporator. When the throttling operation requires the addition of working parts in the refrigerant control it may be objectionable for many applications and, accordingly, it is an object of the present invention to provide an air cooling system including a refrigerant evaporator and an improved arrangement for varying the effective cooling surface of the evaporator.

It is another object of this invention to provide an air cooling system including a refrigerating machine and an improved arrangement for controlling the effective surface of the refrigerant evaporator which shall be of simple and rugged construction and which shall not require additional moving parts in the refrigerant control mechanism.

Further objects and advantages of this invention will become apparent as the following description proceeds, and the features of novelty which characterize this invention will be pointed out with particularity in the claims annexed to and forming a part of this specification.

For a better understanding of this invention reference may be had to the accompanying drawing in which Fig. 1 represents diagrammatically an air cooling system embodying the invention; and Fig. 2 similarly represents a modified arrangement of the system.

Referring now to the drawing, the air cooling system shown in Fig. 1 includes an evaporator 1 arranged to cool the air passing through a duct 2 under operation of a suitable fan or blower (not shown). The evaporator 1 is connected in a closed refrigerant circuit including a compressor 3 driven by a suitable motor 4, a condenser 5, and a liquid receiver 6. Hot compressed refrigerant is delivered by the compressor to the

2

condenser where it is cooled by the passage of suitable cooling fluid over the surface of the condenser and is liquefied, the liquid refrigerant collecting in the receiver 6. From the receiver 6 the liquid flows through a liquid line 7 to a thermostatic expansion valve 8 having a thermal bulb or feeler element 9 secured to the suction line of the evaporator 1 indicated at 10. The evaporator as illustrated, by way of example, comprises four individual coils 11. Each of the coils is supplied with substantially the same quantity of liquid refrigerant from a distributor 12 associated with the thermostatic expansion valve 8, and the outlets of all coils are connected to the suction line 10 acting as a manifold. The coils are thus in parallel to the refrigerant circuit and are also in parallel in the air circuit, each coil serving a separate zone of the air duct so that each coil treats a separate volume of air. During the operation of the system the thermostatic expansion valve 8 operates to maintain substantially constant the value of superheat of the vaporized refrigerant withdrawn through the suction line 10 as determined at the location of the control bulb 9. In order to change the effective surface of the evaporator 1 during the operation of the system, a damper 13 is provided in a position so that it may be moved across the face of the top coil 11 to limit or restrict the passage of air over that coil. The damper 13 is biased to its open position by a spring 14 and is arranged to be closed by a solenoid winding 15 arranged to move an armature 16 to the right upon an increase in the current flowing through the winding. The energization of the winding 15 is controlled by a variable resistor 17 actuated by a device which is responsive to a condition of the air and has been illustrated as a coiled bimetallic element 18 responsive to the temperature of the air entering the evaporator. The coil 15 is connected to a source of electric current 19 through the resistance 17 and the thermostatic element 18 is arranged to reduce the amount of resistance in the circuit by rotating a contact 20 in a counterclockwise direction upon a decrease in the temperature of the air. Thus the damper 13 is moved gradually into the path of the air flowing over the top coil 11 as the contact 20 is moved gradually in a counterclockwise direction. As the flow of air over the top coil 11 is restricted, less refrigerant is evaporated in the coil and liquid refrigerant flows from the coil into the suction line 10. This liquid refrigerant lowers the resultant temperature at the location of the temperature bulb 9, and the valve

8 closes to reduce the amount of refrigerant supplied to the four coils 11 so that the superheat of the gas is restored to the required value. Since each of the coils then receives less liquid refrigerant, the effective surface of the lower three coils is reduced and the effective surface of the entire evaporator is reduced accordingly. The average temperature of the air leaving the evaporator is thereby raised and overcooling is avoided. It will readily be understood that the operation of the thermostatic control 18 will tend to maintain substantially constant the average temperature of the air passing over the evaporator. The arrangement of the damper 13 thus makes it possible to control the effective surface of the evaporator 1 without providing additional moving parts within the refrigerant circuit and provides a simple and easily constructed device for securing a modulated control of the condition of the air passing through the duct.

In addition to controlling the effective surface of the evaporator in accordance with the temperature of the air to be cooled it may also be desirable to limit the loading of the system to prevent overloading of the motor during temperature conditions of the fluid employed to cool the condenser. In Fig. 1 there is provided an additional damper 21 which is arranged to vary the proportion of air flowing over the lowermost coil 11. This damper is biased by gravity and the flow of air to its open position; however, when the pressure in the condenser rises above a predetermined value a bellows 22 expands and moves a member 23 into engagement with an arm 24 on the damper and moves the damper into the path of the air flowing over the lower coil. Condenser pressure is conducted to the bellows 22 through the usual control tube 25, which is in open communication with the interior of the condenser. The operation of the damper 21 in changing the capacity of the system is the same as that of the damper 13, so that upon restriction of the air flowing over the lowermost coil of the evaporator the load carried by the evaporator is reduced and overloading of the motor is prevented.

In some cases it may be desirable to combine the control functions for air temperature regulation and motor overload prevention in a single mechanism. The air cooling system of Fig. 2 is essentially the same as that of Fig. 1 and corresponding parts have been designated by the same numerals. In this figure a single damper 26, which may be of somewhat greater area than the damper 13 of Fig. 1, is provided in a position to be moved over the face of the uppermost coil 11 and also in its closed position to partially restrict the circulation over the next coil 11. The damper 26 is actuated by an arm 27 which is biased by a spring 28 to the damper opening position. The operation of the damper in response to the control 18 is the same as that of the damper 13 in Fig. 1 and controls the air temperature in the same way. The load carried by the motor 4 is limited by operation of a control bellows 29 which moves against the arm 27 when the temperature of the motor 24 rises above a predetermined value, the temperature being determined by a thermal bulb or feeler element 30 arranged in the motor windings to be responsive to the motor temperature. Thus the motor temperature control will take over and move the damper toward its closed position, if required, regardless of the position determined by the operation of the control 18. The functions performed by both dampers 13 and 21

of Fig. 1 are thus performed by the single damper 26 of Fig. 2 and, as already mentioned, this damper may be made of somewhat greater area than the dampers 13 and 21 in order to close off a part of a second coil should the motor overload control require further restriction after the temperature control has moved the damper to its extreme position in response to the control 18. It will readily be understood that motor temperature or condenser pressure may be employed interchangeably to determine the load condition on the motor.

While the invention has been illustrated in connection with specific forms of apparatus, other modifications will readily occur to those skilled in the art. For example, the number and arrangement of the coils 11 may be varied to suit particular applications, and although the control 18 has been illustrated as arranged in the air stream entering the evaporator other locations may be employed in accordance with well-known practice in the art and the control may be made to respond to humidity instead of temperature if desired.

What I claim as new and desire to secure by Letters Patent of the United States is:

1. An air cooling system comprising a duct arranged for the circulation of air therethrough, a refrigerant evaporator arranged in said duct for cooling the air passing therethrough, said evaporator comprising a plurality of refrigerant conduits each arranged in a separate zone of said duct, said zones being arranged in parallel in relation to the direction of air flow, means for supplying liquid refrigerant to said evaporator and for withdrawing vaporized refrigerant therefrom, a thermostatic expansion valve arranged to control the admission of refrigerant to said evaporator for maintaining a predetermined amount of superheat in the vapor withdrawn from said evaporator, a distributor for directing substantially equal quantities of refrigerant to each of said conduits, and means arranged to change the relative proportion of air flowing over one of said conduits for varying the effective surface of others of said conduits.

2. An air cooling system comprising a duct arranged for the circulation of air therethrough, a refrigerant evaporator arranged in said duct for cooling the air passing therethrough, said evaporator comprising a plurality of refrigerant conduits each arranged in a separate zone of said duct, said zones being arranged in parallel in relation to the direction of air flow, means for supplying liquid refrigerant to said evaporator and for withdrawing vaporized refrigerant therefrom, a thermostatic expansion valve arranged to control the admission of refrigerant to said evaporator for maintaining a predetermined amount of superheat in the vapor withdrawn from said evaporator, a distributor for directing substantially equal quantities of refrigerant to each of said conduits, and means including a damper arranged to be moved into the path of air flowing over one of said conduits for changing the proportion of air flowing over said one conduit to vary the effective surfaces of the others of said conduits.

3. An air cooling system comprising a duct arranged for the circulation of air therethrough, a refrigerant evaporator arranged in said duct for cooling the air passing therethrough, said evaporator comprising a plurality of refrigerant conduits each arranged in a separate zone of said duct, said zones being arranged in parallel in

ation to the direction of air flow, means for applying liquid refrigerant to said evaporator for withdrawing vaporized refrigerant therefrom, a thermostatic expansion valve arranged to control the admission of refrigerant to said evaporator for maintaining a predetermined amount of superheat in the vapor withdrawn from said evaporator, a distributor for directing substantially equal quantities of refrigerant to each of said conduits, and means responsive to a condition of the air circulated over said evaporator for changing the relative proportion of air flowing over one of said conduits for varying the effective surfaces of the others of said conduits.

6. An air cooling system comprising a duct arranged for the circulation of air therethrough, a refrigerant evaporator arranged in said duct for cooling the air passing therethrough, said evaporator comprising a plurality of refrigerant conduits each arranged in a separate zone of said duct, said zones being arranged in parallel in relation to the direction of air flow, means for supplying liquid refrigerant to said evaporator for withdrawing vaporized refrigerant therefrom, a thermostatic expansion valve arranged to control the admission of refrigerant to said evaporator for maintaining a predetermined amount of superheat in the vapor withdrawn from said evaporator, means including a refrigerant distributor connected between said evaporator and said valve for connecting said conduits in parallel and for supplying substantially equal quantities of refrigerant to each of said conduits, and means including a damper arranged to be moved into the path of air flowing over one of said conduits for changing the proportion of air flowing over said one conduit to vary the effective surfaces of the others of said conduits.

5. An air cooling system comprising a duct arranged for the circulation of air therethrough, a refrigerant evaporator arranged in said duct for cooling the air passing therethrough, said evaporator comprising a plurality of refrigerant conduits each arranged in a separate zone of said duct, said zones being arranged in parallel in relation to the direction of air flow, means for applying liquid refrigerant to said evaporator for withdrawing vaporized refrigerant therefrom, a thermostatic expansion valve arranged to control the admission of refrigerant to said

evaporator for maintaining a predetermined amount of superheat in the vapor withdrawn from said evaporator, a distributor for directing substantially equal quantities of refrigerant to each of said conduits, a damper arranged in said duct for limiting the circulation of air through one of said zones, means for biasing said damper to its open position, and means responsive to the temperature of air circulated through said duct for actuating said damper to change the proportion of air flowing through said one zone to vary the effective surfaces of the conduits in the others of said zones.

6. An air cooling system comprising a duct arranged for the circulation of air therethrough, a refrigerant evaporator arranged in said duct for cooling the air passing therethrough, said evaporator comprising a plurality of refrigerant conduits each arranged in a separate zone of said duct, said zones being arranged in parallel in relation to the direction of air flow, means including a refrigerant condensing unit for supplying liquid refrigerant to said evaporator and for withdrawing vaporized refrigerant therefrom, a thermostatic expansion valve arranged to control the admission of refrigerant to said evaporator for maintaining a predetermined amount of superheat in the vapor withdrawn from said evaporator, a distributor for directing substantially equal quantities of refrigerant to each of said conduits, means responsive to a condition of the air circulated over said evaporator for changing the relative proportion of air flowing over one of said conduits for varying the effective surfaces of the others of said conduits, and means responsive to the loading of said condensing unit for modifying the operation of said last mentioned means to prevent overloading of said unit.
